UNITED STATES PATENT OFFICE

CURTIS S. CRAFTS, OF OAK PARK, ILLINOIS, ASSIGNOR TO THE GOSS PRINTING PRESS COMPANY, OF CHICAGO, ILLINOIS, A CORPORATION OF ILLINOIS

FOLDING MECHANISM

Application filed January 19, 1932. Serial No. 587,498.

The present invention relates to folding mechanism and more particularly to new and useful improvements in the folding mechanism of rotary printing presses for displacing certain of the papers in the delivered stack and thereby dividing the stack into groups each of which contains a predetermined number of papers.

Objects and advantages of the invention will be set forth in part hereinafter and in part will be obvious herefrom; or may be learned by practice with the invention, the same being realized and attained by means of the instrumentalities and combinations pointed out in the appended claims.

The invention consists in the novel parts, constructions, arrangements, combinations and improvements herein shown and described.

20 The accompanying drawings, referred to herein and constituting a part hereof, illustrate one embodiment of the invention, and together with the description, serve to explain the principles of the invention.

25 Of the drawings:

Figure 1 is a side elevation illustrating one embodiment of the present invention, certain of the parts being broken away;

30 Figure 2 is an end elevation of the mechanism shown in Figure 1; and

Figure 3 is a fragmentary view similar to Figure 1 and showing the parts in a different position.

35 The present invention is directed to providing means for insuring a uniform arrangement or stacking of the folded products as they are delivered regardless of the speed of operation of the folding mechanism. Another object of the invention is the provision of such means which will not interfere with the normal operation of the displacing or product counting means.

40 In the usual form of delivery mechanism employed in connection with rotary folding mechanism for high speed printing presses, the folded products are individually delivered into the pockets of a rotary fly which lowers and turns the product, finally laying it on a series of moving delivery belts. When 45 such a mechanism is operated at high speed,

the movement of the product by the rotary fly creates a relatively large amount of centrifugal force tending to throw the products out of the pockets of the fly. The products are also customarily brought to rest against the 55 stationary stop after which they drop on to the delivery belt; and at high speeds there is a considerable tendency of the products to bounce away from the stop instead of dropping vertically on to the delivery belts. These 60 uncontrolled movements of the products interfere with the uniform stacking on the delivery belts, rendering it difficult, and often impossible, to determine which of the products is the one indicating the count. Consequently, an incorrect number of products may be picked up by the operator from the stack on the delivery belts.

In accordance with the present invention, means are provided for preventing movement 70 of the products by centrifugal force, and for holding the product against bouncing as it is suddenly brought to rest and dropped on to the traveling delivery belts.

Referring now in detail to the embodiment 75 of the invention illustrated by way of example in the accompanying drawings, the rollers 1 and 2 of the transverse folder, which makes the final cross-fold in the newspaper, are journaled in the side frames 3. A rotary fly 4 has its shaft 5 also journaled in frames 3 and is provided with a plurality of arms 6, between which are the pockets 7 for receiving completed newspapers as they are individually delivered from the folding rollers 85 1 and 2.

As is usual, the rotary fly 4 is rotated and the newspapers are individually delivered into the pocket 7, and by rotation of the fly 90 they are brought against a stationary stop and finally dropped on to a delivery device, such as a travelling belt 8 running over roller 9 journaled in the arms 10. The papers, as delivered on the belts 8, are arranged in a row or series, with certain of said papers displaced from the otherwise uniform arrangement to indicate groups, each of which contains a predetermined number of newspapers.

100 For effecting this periodic displacement of

certain of the newspapers, any suitable form of mechanism may be provided such as that shown in the prior patent to Evensen, No. 1,825,998 of 1931. As embodied, a kicker or flipper arm 15, adapted to operate periodically upon a folded paper in the fly and prevent its coming back into the fly as far as it otherwise would just as it is delivered, is mounted on a shaft 15', connected by link 16' to arm 16. Arm 16 is mounted on a shaft 17 journaled in the machine frame 3, and at one end of said shaft is an arm 18 provided at its end with a cam roller 19 cooperating with the slowly driven cam 20, geared to and driven from the folding mechanism.

In its general features, the mechanism just described in detail is similar to the usual form of delivery mechanism, and if operated at high speeds, causes the irregular delivery of the products as they are laid on the delivery belts 8. The sudden stopping of the newspapers as their folded edge is brought into contact with the stop 21, causes them to bound back and away from the stop and prevents their dropping vertically on to the delivery belts. Furthermore, the centrifugal force caused by the rapid movement of the newspapers around shaft 5 as a center, also tends to move the papers outwardly of the fly, the extent of this movement depending on the speed of the press.

In accordance with the present invention, means are provided for retaining the products within the pockets during a considerable portion of their arcuate travel, holding them against outward movement until the folded edge engages the stop 21, thus preventing bouncing of the product and insuring that the product drops vertically on to the delivery belts 8. As embodied, a plurality of guides are provided closely adjacent to the fly 4 and positioned to engage the outer edge of the newspaper product. Guides 25, mounted on rods 26 and 27, are positioned directly beneath the folding roller 1 and extend downwardly and to one side of the fly 4. Guide 25 is provided with movable extension 28, independently mounted on shaft 29 which is journaled in the side frames 3, and extension 28, as well as guide 25, is formed with an inner face substantially concentric with the shaft 5, and spaced from the fly a distance just sufficient to permit it to engage with the outer edge of the newspapers as they are received within pockets 7 and moved by the fly 4. As embodied, a plurality of sets of guides 25, 28 are employed, one set between each pair of arms 6, but any other suitable number may be employed. Movable guide 28 is of sufficient length so that the outer edge of the newspaper is moved clear of its lower end just after the inner or folded edge of the paper has been brought to rest against stop 21, at which time the rotational movement of the newspaper

ceases and it begins to drop on to the belts 8. This lower portion of guide 28 not only serves to prevent irregular delivery due to centrifugal force, but holds the newspaper against bouncing as it comes to rest against the stationary stop 21.

Means are also provided for preventing interference of guide 28 with the normal operation of the kicker 15, and this is effected by moving guide 28 outwardly in timed relation with the movement of kicker 15. For this purpose, the kicker actuating lever 16 is rigidly connected with a lever 34 fast on shaft 17 and connected by link 35 to an arm 36 fastened to and at one end of shaft 29. As kicker 15 is moved to displace one of the newspapers, movable guide 28 is also moved away from the fly 4 to a position such that it does not interfere with the intended displacement of the group-indicating newspaper. This operation is shown in Figure 3 of the drawings, which illustrate the position of the parts at the instant of contact of the newspaper with the kicker 15.

The invention in its broader aspects is not limited to the specific mechanisms shown and described but departures may be made therefrom within the scope of the accompanying claims without departing from the principles of the invention and without sacrificing its chief advantages.

What I claim is:

1. A delivery mechanism for high speed folders including in combination a rotary fly into which folded products are delivered, a moving surface onto which the products are placed by the fly, means for holding the products within the fly during a portion of its revolution, means for displacing certain of said products as said products are delivered and means for moving said holding means to permit normal operation of the displacing means.

2. A delivery mechanism for high speed folders including in combination a rotary fly into which folded products are delivered, a moving surface onto which the products are placed by the fly, means for retaining the products within the fly during a portion of its revolution, means for displacing a product each time a predetermined number of products has been delivered and means for moving said retaining means to permit operation of the displacing means.

3. A delivery mechanism for high speed folders including in combination a rotary fly into which folded products are delivered, a moving surface onto which the products are placed by the fly, a guide adjacent to said fly and preventing outward movement of the products except at the bottom of travel of said products and means for periodically moving said guide out of operative position.

4. A delivery mechanism for high speed folders including in combination a rotary

fly into which folded products are delivered, a moving surface onto which the products are placed by the fly, a guide adjacent to said fly and preventing outward movement 5 of the products except at the bottom of travel of said products, a pivoted member mounted adjacent to the bottom of said guide and means for periodically moving said pivoted member away from said fly.

10 5. A delivery mechanism for high speed folders including in combination a rotary fly into which folded products are delivered, a moving surface onto which the products are placed by the fly, a guide adjacent to said fly and having a pivoted member mounted adjacent to its lower end, said guide and pivoted member serving to retain the products within said fly until they are brought into proximity to said moving surface and means 15 for periodically moving said pivoted member away from said fly.

6. A delivery mechanism for high speed folders including in combination a rotary fly into which folded products are delivered, a moving surface onto which the products are placed by the fly, a guide adjacent to said fly and having a pivoted member mounted at its lower end, means for displacing a product each time a predetermined number 25 of products has been delivered and means for moving said pivoted member away from said fly each time said displacing means is operated.

30 7. A delivery mechanism for high speed folders including in combination a rotary fly into which folded products are delivered, a moving surface onto which the products are placed by the fly, a guide adjacent to said fly and having a pivoted member mounted at its lower end, means for displacing a product each time a predetermined number of products has been delivered and means for moving said pivoted member away from said fly in unison with the operation of the displacing means.

35 8. A delivery mechanism for high speed folders including in combination a rotary fly into which folded products are delivered, a moving surface onto which the products are placed by the fly, a guide adjacent to said fly and having a movable member mounted at its lower end, a kicker for displacing a product as it is delivered each time a predetermined number of products has been delivered and means for moving said member away from said fly in unison with the operation of the displacing means.

40 9. A delivery mechanism for high speed folders including in combination a rotary fly into which folded products are delivered, a moving surface onto which the products are placed by the fly, a guide adjacent to said fly and having a movable member mounted 45 at its lower end and means for periodically

moving said movable member away from said fly.

10. A delivery mechanism for high speed folders including in combination a rotary fly into which folded products are delivered, a moving surface onto which the products are placed by the fly, a guide adjacent to said fly and having a movable member mounted at its lower end, and means for periodically moving said movable member and for displacing a product as it is placed on said moving surface.

11. A delivery mechanism for high speed folders including in combination a rotary fly into which folded products are delivered, a moving surface onto which the products are placed by the fly, a guide concentric with said fly and spaced therefrom to engage the outer edge of the products as they are moved by said fly, said guide having a movable portion, a kicker periodically operated to displace certain of said products and means for moving said portion as said kicker is operated.

15 In testimony whereof, I have signed my name to this specification.

CURTIS S. CRAFTS.
